UNITED STATES PATENT OFFICE.

CORYDON J. PETRIE, OF GENEVA, OHIO.

GAS-STOVE.

1,172,629.

Specification of Letters Patent. Patented Feb. 22, 1916.

Application filed October 12, 1915. Serial No. 55,538.

To all whom it may concern:

Be it known that I, CORYDON J. PETRIE, a citizen of the United States, residing at Geneva, in the county of Ashtabula and State of Ohio, have invented certain new and useful Improvements in Gas-Stoves, of which the following is a specification.

This invention relates to certain new and useful improvements in gas stoves.

10 The primary object of this invention is the provision of a stove for fluid fuel and especially adapted for natural gas, the same being employable both as a heater and a cooking stove.

15 Another object of the invention is to provide a gas stove provided with an extended area for the gas flame and having a tortuous path of travel for the products of combustion whereby the maximum quantity of heat 20 is utilized in the stove before exhausting the products of combustion through the outlet flue.

25 A still further object is to provide a stove for natural gas which is easy to manufacture being constructed with a removable arrangement of gas-directing partitions providing increased radiation, enhancing the efficiency of the stove, provision being also made to draw inwardly the cold air beneath 30 the stove for warming the same.

With these general objects in view and others that will appear as the nature of the invention is better understood, the same consists in the novel combination and arrangement of parts hereinafter more fully described, illustrated in the accompanying drawings, and pointed out in the appended claim.

In the drawings forming a part of this 40 application and in which like-designating characters refer to corresponding parts throughout the several views:—Figure 1 is a front elevation of the stove. Fig. 2 is a vertical sectional view thereof. Fig. 3 is a 45 vertical transverse sectional view taken upon line III—III of Fig. 2. Fig. 4 is a horizontal transverse sectional view through the stove. Fig. 5 is a vertical transverse sectional view thereof taken upon line V—V 50 of Fig. 2. Fig. 6 is an enlarged perspective view of the radiating frame illustrating its position within the stove. Fig. 7 is a horizontal transverse sectional view of a circular form of stove embodying the present 55 invention, and Fig. 8 is a perspective view of a portion of the latter.

Referring more in detail to the drawings, a substantially cubical form of casing 10 is provided for one form of the stove mounted in substantially the usual manner upon four corner legs 11 and the said casing being provided with a forwardly projecting dome 12 and with hinged front double doors 13 beneath the said dome.

60 A gas supply pipe 14 is horizontally positioned transversely through the casing 10 slightly above the bottom 15 thereof and is provided with diagonally arranged slits 16 upon its upper side for furnishing a burner for the stove positioned adjacent to a forwardly inclined baffle plate 17 secured to the casing bottom 15 and extending in spaced relations beneath the top 18 of the casing, the said plate being covered with a non-combustible fiber facing 19 such as asbestos. The casing bottom 15 has an upturned portion 20 adjacent the burner pipe 14 leaving an open slot 21 beneath the said burner pipe for admitting air to the burner and assisting the combustion of the fluid fuel, the blaze from the burner being distributed over the plate facing 19 as the flame ascends.

65 A plurality of air tubes 22 are vertically arranged between the casing bottom 15 and top 18 having entrance openings 23 at the bottoms thereof and outlets 24 at their tops. A detachable cover 25 is provided upon the casing with a projecting side bead 26 and a centrally arranged knob or handle 27, while the said cover is provided with a plurality of perforations 28 after the manner of a radiator for allowing the heated air to escape therethrough as illustrated by arrows in Fig. 2 of the drawings.

70 A frame is arranged within the casing 10 for performing the dual function of providing additional radiation as well as an extended path of travel for the products of combustion and the same consists of three spaced transverse plates 28, 29 and 30 arranged in parallelism and having perpendicularly positioned connecting plates 31 and 32 between the adjacent ones of said three plates, the said connecting plates being of less width than the transverse plates as best illustrated in Fig. 6 of the drawing. This radiating frame so formed is removably positioned within the casing 10 and the forward plate 28 thereof is provided with an opening 33 at one forward lower corner thereof, while the intermediate plate 29 is

arranged with a similar opening 34 at its opposite lower corner and the rear plate 30 has a similar opening 35 at its lower corner corresponding to the first-named plate opening 33.

An inclined baffle plate 36 is positioned between the rear plate 30 and the rear wall 37 of the casing 10 and has its lower end secured to the casing bottom adjacent the 10 said plate opening 33, while an outlet pipe 38 is provided for the products of combustion communicating through the casing wall 37 at a point beneath the said plate 36. It will thus be seen that by igniting the fluid 15 fuel such as gas at the burner slits 16 of the inlet pipe 14, the plate facing 19 will be formed in a sheet of flame imparting heat to the stove, while the products of combustion will pass rearwardly over the top of 20 the baffle plate 17 thence through the bottom opening 33 of the plate 28 and over the top of the connecting plate 31 and through the opening 34 of the intermediate plate 29 and thence over the top of the connecting 25 plate 32 and out through the bottom opening 33 of the rear plate 30 where the same will ascend as directed by the plate 36 and then descend and be exhausted through the outlet flue 38 of the casing. The heating 30 of the radiating frame formed of the plates heretofore mentioned as well as the heating of the casing 10 generates a high degree of heat for any purposes desired, while the path of travel required of the products of 35 combustion by means of the radiating frame allows substantially the entire heat to be utilized before the same is exhausted through the outlet flue 38. The heating of the air within the tubes 22 provides an upward 40 draft therethrough for exhausting the cold air from beneath the casing 10 and heating the same within the tubes 22 for passing outwardly through the upper ends thereof and through the perforations 28' of the 45 stove cover 25.

In Figs. 7 and 8 a circular form of the stove is provided in which the invention is also embodied and the same broadly consists of a cylindrical member having an outer cylindrical casing 39 and inner casing 40 arranged concentrically therewith, a top 41 and a bottom 42 being arranged for the same. A plurality of air tubes 43 are vertically arranged connecting the top and bottom 45 members 41 and 42 for opening at both ends for allowing the air to pass therethrough. A burner 45 is arranged within the casing at the forward side thereof, while an outlet pipe 46 is arranged at its rear side. 60 Transverse partitions 44 are arranged spaced apart between the said pipes 43 and the said burner 45 and outlet 46, the partitions ad-

jacent the said burner 45 having upper corner openings 47 at their inner sides, while the remaining partitions 44 are provided with similar openings 48 alternately arranged at the lower outward corners and the upper inner corners thereof, so that the partitions at the opposite sides of the outlet pipe 46 are arranged at the lower outer corners of the same.

In this form of the invention, it will be seen that the operation is the same as in the preferred embodiment thereof, the products of combustion passing from the forwardly arranged burner 45 around the partitions 44 until they pass outwardly through the rear flue 46, the air pipes 45 carrying the heated air upwardly through the stove and exhausting the same at the top thereof 80 into the room.

The invention therefore as shown by the embodiments thereof herein illustrated, provides an efficient heating means for a stove casing adapted for the utilization of fluid fuel and is economical in its use by reason of its conservation of a high percentage of the products of combustion emanating from the burner.

While the form of the invention herein shown and described is what is believed to be the preferred embodiment thereof, it is nevertheless to be understood that minor changes may be made therein without departing from the spirit and scope of the invention as claimed.

What I claim as new is:

A stove including a casing, a burner pipe arranged therein adjacent one end, a forwardly inclined baffle arranged adjacent the burner extending from the stove bottom to a point adjacent the top thereof, a plurality of spaced partitions positioned transversely of the stove and extending from the bottom to the top thereof, aligned partitions positioned longitudinally of the stove between the transverse partitions and extending from the bottom of the stove to a point adjacent the top thereof, an inclined baffle positioned in the compartment between the rear wall of the stove and the rear transverse partition, and vertical air flues between the transverse partitions at opposite sides of the baffles, said transverse partitions having openings at the lower corners thereof, the openings in adjacent partitions being at opposite sides thereof to cause a tortuous passage of the heat from the burner.

In testimony whereof I affix my signature in presence of two witnesses.

CORYDON J. PETRIE.
